Attorney

UNITED STATES PATENT OFFICE

GEORGE E. ROBERTS, OF ELKHORN, NEBRASKA

ROTARY PUMP

Application filed January 20, 1928. Serial No. 248,099.

This invention relates to rotary pumps and has for its principal object to provide a means whereby liquids and particularly heavy oils may be pumped with the minimum of manual effort.

Another object of the invention is to provide a device of few and simple parts so that manufacture will be economical and the device will be comparatively durable without replacement of worn parts.

Other objects and advantages will be apparent from the following detailed description in which:

Figure 1 is a side view of the new device with its cover or face-plate removed, parts being broken away and in section.

Figure 2 is a vertical sectional view taken along the dotted line 2—2 of Fig. 1, with a handle applied to its shaft, and;

Figure 3 is a top plan view of a fragmentary portion or segment of a cylinder member showing a piston applied thereto.

Referring now to the drawing for a more particular description in which like parts are denoted by like or corresponding numerals of reference throughout the several views, the numeral 10 indicates a housing preferably provided with an annular flange 11, and a bushing 12 within which one end of a shaft 13 is journalled. The face-plate 14 is similarly provided with a removable and replaceable bushing 15 adapted to provide a bearing for the shaft 13. The face-plate 14 is secured to the housing 10 in a removable manner by any suitable means such as the stud bolts 16, best shown in Fig. 1.

Upon one end of the shaft 13, I provide a handle 17 for the manual propulsion of the later described parts, it being understood that, at desired times, a grooved or plain pulley may be substituted for the handle 17 in instances where it is desired to operate the pump by means of a motor, engine or other suitable source of power other than by hand.

As best shown in Fig. 1, the shaft 13 is preferably located centrally of the device and upon said shaft and secured thereto by any suitable means such as the splined keys 18, I mount a cylinder block 19. The cylinder

block 19 is provided with a plurality of cylindrical recesses 20, the preferred number of cylinders being 4. The cylindrical recesses are provided with slots 21 upon opposite sides of the cylinder block. Within each cylindrical recess 20 I provide pistons 22 adapted to have reciprocating motion by means later described. Each piston 22 is provided with anti-friction rollers 23 mounted upon their wrist-pins 24, said pins projecting outwardly from the flat segmental surfaces 22' which are parallel with each other upon opposite sides of the pistons' wall. The rollers 23 are adapted to extend beyond the side walls of the cylinder block and be received within the grooves 25 formed within the walls of the face-plate 14 and housing 10.

The grooves 25, as best shown in Fig. 1, are located eccentric with respect to the shaft 13 for purposes later described.

The housing 10 provides a segmental intake reservoir 26 upon one side of the device which is in communication at all times with an inlet pipe or similar conduit 27. The pipe 27 is in communication at all times with a tank or other container not shown.

A conventional check-valve, not shown, is preferably placed in the pipe 27 closely adjacent to its mouth and to the reservoir 26. The function of the check-valve is to permit oil to flow through the pipe 27 towards the reservoir by opening and to prevent the escape of said oil from the reservoir and through the pipe 27 by means of said valve closing. It is understood that the tank may be at a remote distance from the device such as being buried under the ground about filling stations or other oil dispensing depots.

Upon the side of the device opposite to the reservoir 26, I provide an outlet duct 28 which is in communication at all times with a pipe 29, said pipe 29 leading to a suitable point for dispensing the liquids.

The device may be supported above the level of the ground by any suitable means such as its legs 30.

As best shown in Fig. 1, during rotary movements of the cylinder block, its perimeter or outer edge will have bearing against or be positioned closely adjacent to a projection

or cut-off 31 of the flange 11. It will be noted that since the annular segmental length of the flange 31 is greater in distance than the diameter of the pistons 22 that the projection 31 will function as a cut-off for preventing communication between the reservoir 26 and the outlet passageway 28. Likewise, I provide a projection 32 preferably diametrically opposite to the projection 31 which has a similar function.

In operation, the cylinder block 19 is rotated in the direction of the arrow 33 and referring to the piston which is adjacent the projection 32 in Fig. 1, it will be noted that it is at the end of its discharge stroke and that when it comes in alignment with the inlet pipe 27 and enters the area of the reservoir 26 that it will start an intake stroke by reason of the fact that its rollers 23, which are in contact at all times within their grooves 25, will cause the piston to move towards the shaft 13 since the grooves 25 are formed eccentrically with respect to said shaft. The said piston during its above described movement will cause the liquid in the reservoir 26 to load or fill its cylinder during its intake stroke which is completed when the piston reaches a position adjacent the projection 31. After passing the projection 31, the piston will be caused to start a discharge stroke by reason of the fact that the grooves 25 diverge outwardly away from the shaft 13 at said time. When the piston again reaches the position adjacent the projection 32, it has completed its discharge stroke, the oil or liquid being forced into the duct 28 and pipe 29. As the liquid becomes removed from the reservoir 26, a partial vacuum will be created in said reservoir 26 and the inlet pipe 27, thereby causing a suction of the liquid from its source of supply or the above mentioned tank. The other pistons operate similarly to the one above described and are but a multiple thereof.

In order to relieve back pressure from the pistons 22, at their sides nearest the shaft 13, I provide by-pass ducts 34 which, as best shown in Fig. 1, establish communication between all of the cylinders in a manner whereby air or liquid contained in the cylinders and upon the sides of the pistons nearest the shaft 13 will become by-passed, pumped or forced from one piston to the other, thereby reducing and relieving back pressure.

I claim as my invention:—

A rotary pump, comprising a housing having inlet and outlet openings in one side separated by a partition extending inwardly from the peripheral wall of the housing, said housing having a second partition extending inwardly from said peripheral wall and disposed substantially opposite to said first partition to provide between the opposite sides of the partitions intake and exhaust chambers, a shaft centrally mounted in the hous-

ing and adapted to be turned, a solid cylinder block mounted on the shaft to turn therewith and fitting between the inner ends of said partitions, said cylinder block having radially disposed cylinder openings therein opening through the peripheral face of the block and having radial slots in the opposite sides of the block opening into said cylinder openings, and pistons fitting in the cylinder openings and having pins projecting through said radial slots and beyond the sides of the block, said housing having annular grooves in its opposite inner flat walls for the reception of said pins, said grooves being eccentrically offset from the shaft toward said inlet and outlet openings, and said cylinder block having passages therein interconnecting the inner ends of the cylinder openings to relieve pressure against the inner ends of the pistons.

In testimony whereof, I have affixed my signature.

GEORGE E. ROBERTS.
